CLAIM

I claim the ornamental design for a hygiene cap for an aerosol generator, as shown and described.

DESCRIPTION

FIG. 1 is a top front perspective view of a hygiene cap for an aerosol generator showing the claimed design;

FIG. 2 is a bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines in the drawings illustrate portions of the hygiene cap for an aerosol generator that form no part of the claimed design.
